P. D'ANGELILLO,
MILK BOTTLE HOLDER,
APPLICATION FILED MAR. 9, 1918.

1,296,369.

Patented Mar. 4, 1919.

UNITED STATES PATENT OFFICE.

PELLEGRINO D'ANGELILLO, OF NEW YORK, N.Y.

MILK-BOTTLE HOLDER.

1,296,369.

Specification of Letters Patent.

Patented Mar. 4, 1919.

Application filed March 9, 1918. Serial No. 221,467.

To all whom it may concern:

Be it known that I, PELLEGRINO D'ANGELILLO, a citizen of the United States, and a resident of the city of New York, borough 5 of Manhattan, in the county and State of New York, have invented a new and Improved Milk-Bottle Holder, of which the following is a full, clear, and exact description.

10 This invention relates to a holder for milk bottles and has for an object the provision of an improved construction which may be slidingly fitted on to a door and after the door has closed be automatically locked 15 thereby against removal until the door is opened.

Another object in view is to provide a milk bottle holder which automatically remains unlocked when an empty bottle is positioned therein and which becomes automatically locked when a full bottle is placed therein.

In the accompanying drawing:

Figure 1 is a fragmentary side elevation 25 of the inside of a door showing an embodiment of the invention applied thereto.

Fig. 2 is a sectional view through Fig. 1 on line 2—2.

Fig. 3 is a fragmentary sectional view 30 similar to the lower part of Fig. 2, but showing a full bottle in position.

Referring to the accompanying drawing by numerals, 1 indicates a floor and 2 a door of any desired kind. On the outer face of 35 the door a slide 3 is provided which extends preferably for a short distance along the door and has the end opposite the edge 4 of door 2 closed by a securing bolt or rivet, or any other desired manner. In case this 40 end is not closed the slide 3 could extend entirely across the door so that when tongue or flange 5 connected to the top 6 of the box or casing 7 is interlocked therewith said top and the box 7 cannot be moved or swung outwardly away from the door. To hold the bottom 8 of box 7 in proper position one or 45 more guides or member 9 are provided which may be formed integral with the box 7 if the box is made of metal, or may be secured thereto if the box is made of wood or other material.

In applying the box to the door the bottle is first inserted by the house wife and then the door 2 opened, after which the box is 50 slid along the hook or guide 9 beneath the door 2 and the tongue 5 engaging the slide 3.

The box 7 is provided with a front wall 10 at the lower part and a door 11 at the upper part, said door being secured to the lower part 10 by a hinge 12, which is preferably 60 automatically closed by spring 13 so that the milkman may place the bottle in position and then merely release the door, after which it will automatically close and the bottle will eventually rest on the catch 14 at 65 the bottom of the box so that said catch will engage spring 15 and will also engage the stop 16 whereby the door cannot be again opened. The catch 14 is connected to a bar or plate 17 which extends upwardly along 70 wall 10 when the door 11 is closed and overlaps door 11 to any desired extent so that it may be rigidly secured thereto. This is necessary in order to cause the catch 14 and associate parts to assume the dotted position 75 shown in Fig. 3 when the empty bottle is being removed, or a filled bottle applied to the device. The plate 17 is provided with upstanding lugs 18 and 19 (Fig. 1) in which are journaled a rod 20, which rod merges 80 into bottle supporting arms 21 and 22. A spring 23 surrounds the rod 20 between the upstanding lugs 18 and 19, said spring engaging arm 22 for resiliently holding the arm in an upward position. The spring is 85 intended to be sufficiently strong to support an empty bottle in the position shown in Fig. 2, whereby the bottle will not rest upon the catch 14 as shown in Fig. 3. When the bottle is in the position shown in dotted lines 90 in Fig. 2 catch 14 is lifted by spring 15 so that the milkman may grasp the knob 24 and open door 11 after which he may easily remove the empty bottle and substitute a full bottle. As soon as the empty bottle is 95 removed spring 23 moves the arms 21 and 22 upwardly to the position shown in Fig. 3, whereupon when the full bottle is inserted said full bottle moves downwardly as soon as door 11 is closed until it engages the 100 catch 14. The weight of the full bottle will overcome the action of spring 15 and consequently hold catch 14 in engagement with the stop 16 and thereby prevent any one from opening door 11. The only way a full 105 bottle can be removed from the box 7 is to open the door 2 and then slide the box off the door after which the bottle may be removed from the inner face which is open.

By the construction and arrangement of the 110 parts 3 and 5 and the hook 9 the box is locked to the door and cannot be removed.

until the door is opened, while by the arrangement of catch 14 and associate parts, and the arms 21 and 22 and associate parts door 2 may be opened when the box is empty or is provided with an empty bottle, and is positively locked against opening when the box is provided with a full bottle.

What I claim is:

1. A milk bottle holder comprising a box 10 for receiving a bottle, a hook at the bottom of said box formed to hook over the under edge of a door when in use, a guide arranged on said door, and a depending ear connected with the upper part of the box 15 interlocking said guide for locking the upper part of the box to said door, said guide being open on the end nearest the edge of the door whereby said ear and said hook may be slidingly positioned adjacent the door and slidingly removed therefrom when the box is being placed on the door or removed therefrom.
2. A milk bottle holder comprising a box, 25 means for connecting said box to a door, a door member hinged to said box, a catch connected with said door member, said catch being moved to a closed position by a full bottle, and a folding support connected to the box adjacent the door member for an 30 empty bottle, said support holding the empty bottle out of contact with the catch whereby said door member may be opened when an empty bottle is in the box and is locked against opening when a full bottle 35 is in the box.
3. A milk bottle holder comprising a box formed with a door, a hinge for supporting the door, a plate connected to the door interiorly and extending from the door to 40 near the bottom of the box, a catch pivotally mounted on said plate at the bottom, a spring normally holding said catch in a lifted position, a stop projecting upwardly from the bottom of the box and positioned 45 to engage the catch when the catch has been depressed against the action of said spring, and a movable spring arranged on said plate above said catch for supporting an

empty bottle when the support is in a lowered position and adapted to be moved out of the way when a full bottle is placed in the box, said full bottle being designed to press the catch so as to engage said lug and thereby prevent the opening of said door.

4. A milk bottle holder comprising a box 55 open at one side, means for connecting the box to a door so that the open side will be closed by the door, a door member forming part of the box, said door member being supported by a hinge, a plate connected 60 with said door member and extending to the bottom of the box, said door member being hinged above the bottom of the box, a spring pressed catch connected to the bottom of said plate, a lug for locking said 65 catch when the spring acting thereon has been compressed, a pair of arms pivotally mounted on said plate adapted to support an empty milk bottle above said catch when in a lowered position, and a spring continually acting on said arms for causing said arms to support the empty milk bottle when in one position and to hold said arms in a position substantially parallel to said door when not engaging an empty bottle. 70

5. A milk bottle holder comprising a closed box having a hinged door with the hinge positioned above the bottom of the box an appreciable distance, a plate connected 75 with said door on the inner face, said plate extending to near the bottom of the box, a spring pressed catch pivotally mounted on said plate at the bottom, a stop connected with the bottom of the box positioned so as to interlock with the catch 80 when the catch is depressed, and a movable support for an empty bottle arranged above the catch provided with a spring for moving the support out of the way when not in use whereby a filled bottle placed in 85 the box when the door is open will automatically pass downwardly and rest on said catch for causing the catch to engage said stop.

PELLEGRINO D'ANGELILLO.
